[57] CLAIM

The ornamental design for a electrocardiograph cable housing, as shown and described.

DESCRIPTION

FIG. 1 is a top view of an electrocardiograph cable housing, showing my new design;

FIG. 2 is a perspective view thereof on an enlarged scale;

FIG. 3 is a top plan view thereof on a further enlarged scale;

FIG. 4 is a right side elevational view thereof;

FIG. 5 is a left side elevational view thereof;

FIG. 6 is a bottom plan view thereof;

FIG. 7 is a front elevational view thereof; and,

FIG. 8 is a rear elevational view thereof.

The broken line showing in FIGS. 1, 4 and 5 is for illustrative purposes only and forms no part of the claimed design.
